UNITED STATES PATENT OFFICE.

FRANK A. ROOSA, OF ORANGE TOWNSHIP, BLACKHAWK COUNTY, IOWA, ASSIGNOR
OF ONE-HALF TO JOHN L. ZEIDLER, OF ST. JOSEPH, MISSOURI.

MACHINE FOR FORMING HOLLOW CONCRETE BLOCKS.

1,374,392.

Specification of Letters Patent. Patented Apr. 12, 1921.

Application filed March 18, 1920. Serial No. 366,843.

To all whom it may concern:

Be it known that I, FRANK A. ROOSA, a citizen of the United States of America, and a resident of Orange township, Blackhawk county, Iowa, have invented certain new and useful Improvements in Machines for Forming Hollow Concrete Blocks, of which the following is a specification.

My invention relates to improvements in machines for forming hollow concrete blocks, and the objects of my improvements are, first, to furnish a machine for this purpose having a troweling former-head or heads rotatably and reciprocably movable through a hollow mold to form a hollowed block therein from concrete or other materials; and second, to supply coöperating and coacting means for intermittently and regularly removing the molds containing the newly-formed blocks from the radius of action of the machine.

I have accomplished the above objects by the mechanism which is hereinafter described and claimed, and which is illustrated in the accompanying drawings, in which Figure 1 is a side elevation of said machine, with parts broken away or shown in longitudinal section, and Fig. 2 is a front elevation of said machine, also having parts broken away, and other parts shown in transverse section.

In said drawings like numerals of reference denote like parts throughout the several views.

The mechanism of said machine is mounted in a skeleton framework, comprising base-timbers 8, to which are fixedly secured standards 3 and 7 connected by cross-timbers such as 60 and 61, and by longitudinally-arranged timbers, such as 4, 5 and 6, but the number, positions and arrangements of the elements of the framework may be varied at will to suit particular dispositions of elements of the machinery to be associated therewith.

1 is a rotatable power-shaft mounted in bearing-boxes 2. The numeral 15 denotes a pair of spaced parallel vertically disposed shafts mounted at the front of said framework rotatably, and also being reciprocable in the direction of their length, having splines 16 which permit the shafts to slide longitudinally through sleeves 66 secured rotatably in bearing-boxes 67 on cross-timbers 59 and 60 of the framework. The lower

parts of said shafts are rotatably mounted in bearing-openings 62 of the boxes 17 mounted on a cross-timber 61. On the lower ends of said shafts 15 are removably mounted troweling former-heads 19, of like form, having a cylindrical lower zone and a conical upper zone, the latter containing superficial hollows, which conformation insures proper rotary troweling of the plastic materials within the hollow rectangular mold 20 mounted in spaced relation about said shafts and former-heads on bottom-pallets 58, within raised rims 68 of the latter. The troweling former-heads are also movable through circular openings 57 in said pallets, 70 as will be explained hereinafter.

The vertical shafts 15 have pintle-pins 14 received in longitudinal slots 13 slidably of the terminal forks 12 of arms 11, the rear ends of the latter being fixedly mounted 75 on a cross-shaft 9, the latter mounted to rock in boxes 10 on the rear standards 3.

A driving-pulley 32 is fixed on the rear part of the power-shaft 1, and a driving-belt 28 is carried about said pulley and 80 thence about an idler 29 whose shaft is mounted in boxes 30 on horizontal timbers 5 and 6, and thence about a driven-pulley or belt-wheel 27, the latter being mounted on the splined shaft 15 to rotate the latter 85 while permitting a vertical reciprocation of the shaft. On the shaft 69 which carries the idler 31 which also carries said belt 28, is a like idler, and the latter, is also another idler 29 and driven belt-wheel 27 carries 90 another belt whereby the other vertical shaft 15 is rotated simultaneously and while under reciprocation.

The arms 11 are swung up and down vertically to impart simultaneous reciprocations to said shafts 15 by the following means. A worm 37 on the power-shaft 1 meshes with and drives a worm-wheel 35 on a cross-shaft 36, the latter rotatably mounted in bearing-boxes on said framework. A cam-wheel 34 is fixedly mounted on the shaft 36 to movably contact its circumferential edge with a cam-roller 33 above it rotatably mounted on one of the arms 11. The rotating shaft 1 thus causes 100 the cam-wheel to rock the arms 11. The form of the cam-wheel is such as to impart to the former-heads 19 an approximately single speed of reciprocatory movement through the mold 20, while causing said 110

heads to rotate without reciprocation a short time at each of the upper and lower limits of reciprocation.

The numeral 21 denotes a vertically movable hopper whose lower part conforms to and fits about the upper end of the mold 20. The numeral 26 denotes a depending rod or arm pivotally suspended from the middle of a cross-rod 65, the latter fixed between 10 the two arms 11. The arm 26 traverses an orifice in a bracket 22 fixed on the hopper 21 and has a head 24 on its lower end. A stop 25 is fixed on said arm above and spaced from said bracket, and a coiled compression 15 spring is mounted on the arm between the stop and the bracket. When the arms 11 swing upwardly the head 24 lifts the bracket and the hopper a short time after the swinging movement begins. When the arms 11 20 swing downwardly, the arm 26, acting upon the yielding spring, seats the hopper without shock upon the mold 20 newly advanced beneath it.

I have provided means for regularly at 25 determined intervals shifting a mold containing a newly formed block from under the lifted former-heads 19. This consists of an endless carrier positioned under said former-heads.

30 Like pairs of sprocket-wheels 49 have their shafts 48 and 51 respectively rotatably mounted in bearing-boxes 52 on standards 53 fixed on the prolonged base-beams 8. Sprocket-chains 50 connect said pairs of 35 wheels with each other. To support the chains and keep them taut and horizontal, vertical plates 55 may be fixed on brackets 54 between the upper and lower parts of each chain, each plate having a horizontal 40 marginal flange or ledge 56 immediately below the upper, and above the lower strand of each chain, and upon which the chains run.

The pallets 58 are pivotally mounted on 45 links of opposite strands of the chain in succession.

The chains 50 are driven forwardly by steps regularly by the following means. A counter-shaft 44 is mounted rotatably in 50 bearing-boxes such as shown in 64 and carries a ratchet-wheel 43. On an arm 41 pivotally mounted on said shaft adjacent the wheel 43 is pivotally mounted a driving-pawl 42 for engaging teeth on the ratchet, 55 being normally held slidingly against it by gravity. An arm 38 is pivoted to one of the arms 11, has a lower terminal head 39 and slides through an eye 40 which is pivotally mounted on the outer end of the arm 41. On the outer end of said shaft 44 is 60 fixed a sprocket-pinion 45, and a sprocket-chain 46 connects said pinion with a sprocket-wheel 47 on the outer end of the prolonged shaft 48. It will be seen that when 65 the arms 11 swing downwardly the arm 38

slides through the eye 40 and the ratchet-wheel 43 is still, the arm 41 being supported by a bracket bar 63, the pawl 42 remaining in engagement with teeth of the ratchet. On the upward swing of the arms 11, during the first part of the swinging movement the arm 38 slides upwardly through the eye 40 without moving the arm 41, but when the head 39 engages the arm 41 it then lifts said arm, causing the pawl to 70 partially rotate the ratchet-wheel forwardly, and by means of the above-described intermediate mechanism the endless carrier is advanced to shift a filled mold 20 from under the lifted former-heads 19, the hopper 21 having just been elevated, simultaneously shifting another mold on the succeeding pallet under the former-heads. 75

Empty molds are constantly replaced on 80 the advancing pallets, while the molds containing the newly formed blocks are as constantly manually removed.

One or more former-heads may be used, and the former-heads may be on the same 90 level, or may have one or more positioned at different levels, as shown, to diminish torsional pull on the material being troweled. The former-heads thus form the block with a compact homogeneous structure, supplying the desired number of hollows therein, whose inner surfaces are smooth and hard due to the troweling action. Variations in these mechanisms are covered by the principles of my invention. 95

Having described my invention, what I 100 claim as new, and desire to secure by Letters Patent, is:

1. In a machine of the character described, an open mold, and a plurality of rotatable spaced troweling bodies movable therethrough, the said bodies being positioned in different relative planes of rotation. 105

2. In a machine of the character described, an open mold, a plurality of rotatable troweling bodies movable back and forth through the mold, spaced apart and from said mold, and coacting mechanisms for rotating said bodies while reciprocating them through the mold, and also adapted to halt translatory movements thereof at the opposite limits of their reciprocations while rotating. 110

3. In a machine of the character described, a translatory carrier, a plurality of pallets mounted thereon, an open top and bottom 120 removably supported on one of said pallets, a plurality of troweling rotatable former-heads mounted to traverse the mold, said pallets each having openings adapted to receive said former-heads therethrough, and coacting mechanisms for simultaneously rotating and reciprocating said former-heads, and for shifting said carrier a determined distance intermittent of the return movement of the former-head to clear the mold. 125

4. In a machine of the character described, an endless carrier, a plurality of orificed pallets mounted thereon, an open top and bottom mold positioned on a pallet, a plurality of rotatable reciprocating troweling former-heads movable back and forth through said mold and the orifices in the pallet on which the mold is supported, and

mechanism to impart a step-by-step movement to said endless carrier, acting to produce each movement at the end of the return movement of the former-heads through said mold. 10

Signed at Waterloo, Iowa, this 1st day of March, 1920.

FRANK A. ROOSA.
